UNITED STATES PATENT OFFICE

WILLIAM E. GARDNER, OF WATERTOWN, MASSACHUSETTS, ASSIGNOR TO GARDNER TOY COMPANY, INC., OF WATERTOWN, MASSACHUSETTS, A CORPORATION OF MASSACHUSETTS

DESIGN FOR A TOY BALLOON

Application filed June 20, 1932. Serial No. 44,143. Term of patent 7 years.

To all whom it may concern:

Be it known that I, WILLIAM E. GARDNER, a citizen of the United States, residing at Watertown, in the county of Middlesex, Commonwealth of Massachusetts, have invented a new, original, and ornamental Design for a Toy Balloon, of which the following is a specification, reference being had to the accompanying drawing, forming a part thereof.

The drawing represents a perspective view of a toy balloon, showing my new design.

I claim:

The ornamental design for a toy balloon as shown.

WILLIAM E. GARDNER.
